UNITED STATES PATENT OFFICE.

HENRY KOEHN, OF SHEBOYGAN, WISCONSIN.

DESIGN FOR A BENT-WOOD CHAIR-SEAT.

SPECIFICATION forming part of Design No. 30,400, dated March 28, 1899.

Application filed February 23, 1899. Serial No. 706,589. Term of patent 7 years.

To all whom it may concern:

Be it known that I, HENRY KOEHN, a citizen of the United States, residing at Sheboygan, in the county of Sheboygan and State of Wisconsin, have invented and produced a new and original Design for Bent-Wood Chair- Seats; and I do hereby declare the following to be a full, clear, and exact description of the same, reference being had to the accompanying drawings, forming a part thereof.

In the said drawings, Figure 1 is a plan view. Fig. 2 is a front elevation; and Figs. 3, 4, and 5, sectional views on the lines 3 3, 4 4, and 5 5, respectively, of Fig. 1, of a bent- wood chair-seat embodying my new design.

My design relates to the new and original shape or configuration of the article.

The leading or essential feature consists in the unitary design for a bent-wood chair-seat made the subject of illustration, comprising the peculiar and novel shape of the top or upper portion A thereof, the rear edge or border a whereof is flat, the horizontal plane or level extending forward to about the points b b on the sides. From these points forward the top is rounded over and down at the sides, as best indicated in Fig. 5 by the lines which said top follows between the lines c d on each side, there being a preliminary downward drop forward, as indicated on same Fig. 5 by the lines between the points b d on each side. The rear outline of the top A is generally rounded, as shown in Fig. 1, while from the points b to the points d in said Fig. 1 the sides follow the general lines of ogees. Forward from the points d to the points e in Fig. 1 the front corners of the seat-top are rounded on the arcs of circles, and from each point e to the front central point f in Fig. 1 the front edge of the top A follows the lines of ogees. Next, taking the central longitudinal line of the chair-seat, as indicated by the sectional view Fig. 3, it will be seen that starting from the central point a' the top A continues on a horizontal line to the point b', thence follows a rounded concave line to about the point c' and a rounded convex line from there to the extreme front point f, the

central longitudinal line of the seat at the point c' being of the same height as at the rear point a'. Between the points c' and f the front half of the seat is on its highest line, and on each side of this central longitudinal high line the top A slopes down on the general lines of ogees between the point d' and the points e' e' in the sectional view Fig. 5 and between the point f and the points f' f' in the front elevation Fig. 2, while, as shown, between said points e' to the points d in Fig. 5 and between said points f' to the points d in Fig. 2 the said front portion of the top gradually rises again on each side and then is depressed at each edge, again following the general lines of ogees. The concavity in the rear half of the seat-top is best shown in the section views Figs. 3 and 4.

Minor features of this design comprise the shape of the front piece B of the supporting-frame, which everywhere is shown of uniform height at its front vertical edge and corresponding both at top and bottom with the shape of the seat-top A. The rear piece C of the supporting-frame is of uniform height throughout and flat and horizontal on both top and bottom, and the side pieces D D of the supporting-frame are flat and horizontal at both top and bottom from the rear as far as the points b b and from that point take an abrupt drop to about the point g, as shown in Fig. 4, and thence rise toward the front; but the top surfaces of said side pieces D D are shaped to conform exactly to the shape of those portions of the seat-top A resting thereon.

Having thus described my invention, what I claim as new, and desire to secure by Letters Patent, is—

The design for a bent-wood chair-seat, as herein shown and described.

In testimony whereof I affix my signature in presence of two witnesses.

HENRY KOEHN.
